MECHANICAL BURGLAR ALARM FOR HOME OR TRANSIENT USE

Filed April 2, 1931

INVENTOR

Arnold A. Schantz,

BY **ATTORNEYS**

UNITED STATES PATENT OFFICE

ARNOLD A. SCHANTZ, OF DETROIT, MICHIGAN

MECHANICAL BURGLAR ALARM FOR HOME OR TRANSIENT USE

Application filed April 2, 1931. Serial No. 527,216.

This invention relates to a portable burglar alarm for home or general use and its object is to provide a small compact device which may be handily carried about in travelling from place to place and may be quickly inserted in operative position between the edge of a door or window and its casing, and is arranged to set off an alarm should someone attempt to force an entrance from the outside.

With the above and other ends in view, the invention consists in providing a self-contained bell and spring mechanism for sounding said bell, together with a carrier adapted to be inserted between the edge of a door or window and its casing or jamb, and a trip or latch arranged to be actuated by the opening of the door or window, to release the spring mechanism and sound the bell. The invention further consists in the particular construction and arrangement hereinafter set forth, and all as pointed out in the appended claims, reference being had to the accompanying drawings in which—

Figure 1 is a plan view of the device with a portion of the bell broken away to disclose the internal operating mechanism;

Fig. 2 is a longitudinal section through a major portion of the device, substantially upon the line 2—2 of Fig. 1;

Fig. 3 is an edge elevation of the device showing the same as applied in use; and

Fig. 4 is a perspective view showing the manner of applying the device to a door and its casing.

As shown in the drawings, 1 indicates a suitable cup-shaped base for housing a spirally coiled spring 2, the outer end of which spring is made fast in any suitable manner, not shown, to said cup and the inner or center end of which spring is secured to a tubular member 3 sleeved upon and rigidly secured to a post 4 by a pin 5, said post being rotatively secured at one end to the bottom wall of said cup at the axis thereof to turn freely. Mounted upon the opposite end of said post 4 is a bell 6, by screwing said end into an axial inwardly extending hub 7 of said bell to support said bell with its rim spaced a short distance from the edge of

said cup 1, said cup being closed by a disk 8 secured in any suitable manner within the cup with one surface of said disk in the plane of the edge of the cup, said disk forming a rigid support for a second disk 9 which is 55 carried thereby and spaced therefrom by means of a plurality of spacers or posts 10 and supported well up within the bell 6. These two disks 8 and 9 and connecting posts 10 thus form a rigid frame within the bell 60 for carrying a train of gearing for putting and holding said spring 2 under tension, together with escapement and clapper mechanism for sounding the bell.

Free to rotate upon the post 4 above the sleeve 3, is a sleeve 11 having a ratchet wheel 12 integral with one end thereof, and to engage said ratchet is a spring pressed pawl 13 pivotally attached to a flange 14 on the upper end of the sleeve 3. Formed integral with the upper end of the sleeve 11, is a large gear 15 adapted to mesh with a small gear 16 on a shaft 17 mounted in bearings formed by the disks 8 and 9 laterally of the gear 15, and also secured on this shaft 17 is a larger gear 18 which is in mesh with a small gear 19 on a second shaft 20 mounted between said disks of the gear frame laterally of the shaft 17. This shaft 20 has secured thereto a notched wheel 21 adapted to be engaged by an escapement lever 22 which is pivoted at 23 with one or the other of its ends in contact with said escapement wheel 21 and said lever 22 is provided with a long curved spring arm 24 provided with a clapper or head 25 on its free end to contact the rim of the bell 6 and sound the same when the notched wheel 21 is turned to vibrate the lever 22.

To securely hold the arm 24 against vibration and thus by the engagement of the escapement lever 22 with the escapement wheel 21, hold the train of gearing against rotation and the spring 2 against unwinding, a stiff spring arm 26 is secured to and depends from the disk 9 to engage intermediate its ends, the inner side of the arm 24 and with a strong spring pressure, press outwardly upon said arm and firmly hold its clapper 25 in contact with the bell rim, thus preventing vibration of the escapement and 100

consequent unwinding of the spring 2 which has previously been wound up by grasping and rotating the bell to turn the shaft 4 which is directly connected to the center end of 5 said spring, the pawl 13 and ratchet 12, holding said spring under tension.

With the spring 2 wound up and held against unwinding as above described, in order to release the arm 24 so that it may be 10 vibrated by the escapement lever 22 and ring the bell through the motion imparted to the escapement wheel 21 by the unwinding of said spring 2 imparting a rapid rotation to said wheel through said train of gearing, it is only necessary to press upon the lower end 15 of said spring arm 26 and to so press said arm, a pin 27 is mounted in a suitable bearing therefor in a bracket 28 secured to and extending outwardly from the cup 1 opposite the lower end portion of said arm 26, the inner end of said pin contacting the said arm.

To move said pin 27 inwardly against the action of said spring arm 26 and thus move said arm away from the arm 24 to permit 20 rapid vibration thereof and ringing of the bell, a lever 29 is pivoted to said bracket 28, at 30 and is formed with a cam or surface 31 engaging the outer end of said pin and arranged eccentric to the pivot 30, so that upon 25 turning of said lever, the said pin 27 will be forced inwardly. This lever 29 is also formed with a shoulder 32 at one end of said cam surface 31 to engage the outer end of said pin 27 and hold said lever 30 with its laterally extending arm 33 extending outwardly from said supporting bracket 28 longitudinally of said pin, and said lever is also formed at the opposite end of said cam surface 31 with a notch 34 to receive the outer end of said pin when said cam lever is turned with its operating arm 33 extending at right angles to said pin and hold said lever in that position. When said lever 29 is turned to this latter position, the 45 bell will thus continue to ring until the spring 2 becomes unwound or said lever is turned back to its original position.

In order that this bell alarm device may be readily attached to a window or door casing 50 35 with the operating arm 33 thereof projecting into the path of swinging movement of the free edge of a window or door 36 mounted in said casing, a supporting bracket 37 is provided for the said alarm device. 35 This bracket 37 is preferably formed of sheet steel and is adjustably secured to the bottom of the cup 1 by providing longitudinal slots 38 in the bracket to receive screws 39 screwed into screw-threaded holes in the cup bottom, and one end of this steel strip forming said bracket, is turned or bent at right angles to form an end portion 40 to engage within the space between the edge of the door 36 and casing 35, and this end portion is formed with 60 spurs or sharp teeth 41 to be forced into said

casing and firmly secure said bracket to the casing against being pushed out by the opening of the door, these teeth 41 being forced into the casing by positioning the bracket and then closing the door, or the device may 70 be held in place by screws passing through holes in the plate 37.

As shown in Fig. 3, the alarm device must be supported by the door casing 35 in such a position that the arm 33 of said device will be 75 in the path of the swinging movement of the edge of the door 36, so that, should the door be forced open, said lever 29 will be turned by the swinging of the door, and to adapt the device to different door or window casings, 80 the alarm device is adjustably attached to the bracket 37 by means of the screws 39 in the slots 38 of the bracket, so that the cup 1 may be adjusted along the bracket to bring the arm 33 in proper relation to the end 40 of the 85 bracket, which end is engaged within the space between the edge of the door or window and the casing.

By this arrangement, a very simple and compact alarm device for the purpose, is provided, and which device may be readily carried about and quickly applied to a door or window and its casing.

Having thus fully described my invention, what I claim is:—

1. A device for the purpose described including a base member, a bell carried by said base, operating means in said base and bell for sounding said bell, means for holding and releasing said operating means and including a lever arm pivotally attached to said base and extending laterally from said base to swing thereon and including means for yieldingly holding said lever arm in the position to which it is turned, and a bracket secured to said base for holding said device with the laterally projecting end of said lever arm in the path of movements of a closure.

2. A device for the purpose described including a base, a spring in said base, a bell mounted on said base, means for winding said spring and holding the same under tension, a clapper for said bell operated by said spring, means for releasing said spring holding means to cause said clapper to operate 110 115 to ring said bell, said releasing means including a lever extending laterally from said base, and a bracket to which said base is secured, for supporting the device with said releasing lever in the path of movement of a closure.

3. An alarm device including a base, a spring in said base, a bell mounted over said base, means for winding said spring and holding the same under tension, a clapper for said bell, means for transmitting motion from said spring to vibrate said clapper and ring said bell, a bracket extending laterally from said base, a lever pivotally attached to said bracket and having an arm projecting there- 125 130

from, means operated by the turning of said lever for releasing said motion transmitting means to ring said bell, and a bracket secured to said base for supporting said alarm device 5 with said arm of said lever in the path of movement of a closure.

4. An alarm device including a base, means carried by said base for sounding an alarm, means for holding said alarm sounding means 10 against operation, a pin carried by said base and movable longitudinally thereinto for releasing said holding means to permit operation of said alarm sounding means, a lever pivotally carried by said base and having a 15 cam portion to engage the outer end of said pin, said lever having an arm to project laterally from said base, and a bracket adapted to be attached to a casing for supporting said base with said lever carried by said base positioned with its arm projecting into the path 20 of movement of a closure within said casing.

In testimony whereof I affix my signature.
ARNOLD A. SCHANTZ.
